CLAIM

The ornamental design for a tool organizer, as shown and described.

DESCRIPTION

FIG. 1 is a perspective view of the tool organizer showing our new design;

FIG. 2 is a front elevational view thereof in a position of non use;

FIG. 3 is a rear elevational view thereof in a position of non use; and,

FIG. 4 is an enlarged top plan view thereof.

The broken line showing of a bucket and tools is for illustrative purposes only and forms no part of the claimed design.
